(30) **Foreign Application Priority Data**

The ornamental design for a control panel for fluid distribution equipment, as shown and described.

Jun. 4, 2021 (IT) 4020211000001508

DESCRIPTION

(51) **LOC (14) Cl.** **10-05**

1. Control panel for fluid distribution equipment
Fig 1.1 is a perspective view of a control panel for fluid distribution equipment, showing my new design;
Fig 1.2 is a left side view thereof;
Fig 1.3 is a top view thereof;
Fig 1.4 is a front view thereof;
Fig 1.5 is an enlarged view of Fig. 1.8 thereof;
Fig 1.6 is another enlarged view of Fig. 1.8 thereof;
Fig 1.7 is a right side view thereof;
Fig 1.8 is another perspective view thereof;
Fig 1.9 is a bottom view thereof.
